(57) **CLAIM**

The ornamental design for a head scarf, as shown and described.

DESCRIPTION

FIG. 1 is a perspective view of a head scarf showing my new design.

FIG. 2 is a front view of the head scarf.

FIG. 3 is a rear view of the head scarf.

FIG. 4 is a left-side view of the head scarf.

FIG. 5 is a right-side view of the head scarf.

FIG. 6 is a top plan view of the head scarf; and,

FIG. 7 is a bottom plan view of the head scarf.

The stippling applied to the head scarf depicts surface shading that demonstrates the contours of the claimed design and forms no part of thereof.

The dash-dot-dash broken lines depict boundary lines that form no part of the claimed design.

The evenly spaced broken lines in FIG. 7 depict features of the head scarf that form no part of the claimed design.

1 Claim, 7 Drawing Sheets
